UNITED STATES PATENT OFFICE

LEE J. GARY, OF CHICAGO, ILLINOIS, ASSIGNOR TO UNIVERSAL OIL PRODUCTS COMPANY, OF CHICAGO, ILLINOIS, A CORPORATION OF SOUTH DAKOTA.

PROCESS AND APPARATUS FOR CONVERTING OILS

Application filed June 9, 1922, Serial No. 566,932. Renewed March 8, 1927.

This invention relates to improvements in process and apparatus for converting oils and refers more particularly to the conversion of heavy hydrocarbon oils into lighter boiling point products, such as gasoline and the like, by subjecting these heavy oils to the action of heat and pressure.

The invention consists in heating the oil, preferably in a continuous coil of small pipe and then passing it to successive enlarged reaction chambers where the oil is further heated and vaporization takes place. Each of these reaction chambers is provided with individual reflux condensing means, which are in turn connected to a vapor line leading to a cooling coil. The arrangement is such that the reflux condensate from any of the reflux condensers can be returned to any or all of the enlarged chambers for further treatment or to the heating coils, or it may be withdrawn from each reflux condenser into a main line and conducted out of the system. In other words, this reflux condensate can be conducted to any part, in or out of the system merely by the manipulation of suitable valves, hereinafter described and explained in detail. The whole system may be maintained under a uniform pressure of the vapors generated therein, or differential pressures may be used.

The single figure in the drawing is a vertical sectional view of an oil cracking apparatus showing my invention.

Referring to the drawing, the oil is conducted from any suitable source of supply through the line 1, regulated by the valve 2, to the pump 3. The discharge side of the pump 3 is connected with line 4 leading into the heating coil 5. The heating coil which, in the present instance, comprises a continuous coil of small diameter pipe, say 2", is mounted in the furnace 6, which is heated by gas burner 7. The oil after being heated in the heating coil 5, is passed through the transfer pipe 8, provided with valves 8' and 8", the latter, in the present instance, being closed and the heated oil passed into the top of the first enlarged chamber. There are four of these chambers shown in the present instance, designated 9, 10, 11 and 12 re-

spectively, which chambers are provided with oil transfer lines 13, 14 and 15 and with vapor transfer lines 16, 17 and 18. It is understood, of course, that more or less of these chambers may be provided, if desirable. 55 These chambers are so mounted in the furnace 19, which is heated by means of burner 20 and provided with stack 21, that their upper and lower portions are outside of the fire zone. Each of these chambers is provided 60 with a residuum drawoff indicated at 22, 23, 24 and 25, regulated by valves 26, 27, 28 and 29 respectively and with vapor outlets 30, 31, 32 and 33. These vapor outlets lead into the dephlegmators or reflux condensers 34, 65 35, 36 and 37, which in turn are provided with vapor outlet lines 38, 39, 40 and 41 leading into the vapor line 42. The vapor line 42 is provided with valves 42a, 42b, 42c. 70 This vapor line 42 in turn is connected to the condensing or cooling coils 43, seated in condenser box 44, connected by pipe 45 with receiver 46. The receiver 46 is equipped with pressure gauge 47, liquid level gauge 48, pressure relief valve 49, and drawoff line 50, 75 regulated by valve 51.

Referring again to the dephlegmators 34, 35, 36 and 37, they are provided with the cap portions 52, 53, 54 and 55, extending over the vapor outlets 30, 31, 32 and 33, to allow the 80 vapors free ingress into the dephlegmators but preventing any condensed liquids from falling back into the enlarged chambers 9, 10, 11 and 12. Each dephlegmator is provided with a reflux condensate drawoff line 85 indicated at 56, 57, 58 and 59 regulated by the valves 60, 61, 62 and 63, leading into the drawoff line 64. This drawoff line 64 is provided with the valves 65, 66, 67 and 68 for regulating the flow of condensate therethrough. 90 This line 64 is also provided with drawoff pipes 69, 70, 71 and 72 controlled by the valves 73, 74, 75 and 76, leading into the chambers 9, 10, 11 and 12. The pipes 69, 70, 71 and 72 preferably extend below the liquid level in the enlarged chambers, as shown. The dephlegmators 35, 36, 37 are also provided with reflux drawoff pipes 77 and 78 and 79, controlled by valves 80, 81 and 82, 95 which lead into the preceding reacting chamber. 100

ber, below the liquid level thereof. For the purpose of drawing off any condensate either from the line 64 or from the dephlegmator 37, I provide a drawoff line 83, controlled by 5 valve 84, and leading to any suitable storage. The vapor transfers 16, 17 and 18 are provided with the valves 85, 86 and 87 for the purpose of controlling the flow of vapors therethrough and also for the purpose of controlling 10 the pressure maintained on each chamber. The vapor lines 30, 31, 32 and 33 are also provided with the valves 88, 89, 90 and 91 for the same purpose. Liquid level gauge 92 is provided on the chamber 12 for the purpose of ascertaining the liquid level therein.

One method of operation is as follows: The oil is charged into the heating coils 5, through the pump 3 and there heated to a temperature of say, 400 degrees F. The 20 heated oil is then forced through the transfer line 8, the valve 8' being opened and the valve 8'' closed, into the chamber 9, where the lighter boiling point fractions vaporize instantly and pass up into the dephlegmator 34, 25 the valve 88 being opened and the valve 85 closed. The unvaporized liquid in the chamber 9 is subjected to further heat and when this liquid reaches the level of the liquid transfer pipe 13, it will overflow into the 30 chamber 10. As the level in the chamber 10 rises, it will overflow into chamber 11 through the transfer pipe 14 and this operation repeated in the tank 12 by means of the pipe 15, until the chambers are all at the same level 35 as indicated by the liquid level gauge 92. The liquid level may be maintained uniformly throughout the chambers by manipulation of the valve 29 on the drawoff line 25, or the level maintained by manipulation of the 40 valves on the drawoff pipes at the bottom of each chamber, which drawoff pipes, as stated, are outside of the fire zone. Valves 85, 86, 87 will remain closed, the valves 88, 89, 90 and 91 opened to permit the vapors from 45 each chamber to flow into the dephlegmator above it. The vapors which are not condensed in the reflux condensers or dephlegmators 34, 35, 36 and 37, will flow into the vapor line 42 to the condenser 43, where 50 they will condense and flow into the receiver 46. The reflux condensate in these reflux condensers is drawn off through the lines 56, 57, 58 and 59, the valves 60, 61, 62 and 63 being opened; valves 80, 81, 82, 73, 74, 75 55 and 76 being closed; and the valves 65, 66, 67 and 68 opened. This reflux condensate will then flow back to the heating coils, through a continuation of the line 64, the valve 93 being opened, and valve 94 on line 60 95 being closed. A pressure of say, 125 pounds to the square inch, may be maintained throughout the system, and the oil in the enlarged chambers heated to a temperature of say, 750 degrees F.

Another method of operation would be to

close the valves 93, 94, 65, 66, 67, 68, 61, 62, 63; and open the valves 80, 81 and 82, 60 and 73, thus allowing the reflux condensate from the reflux condensers 35, 36, and 37, to flow back into the preceding chamber for retreatment and the condensate from the reflux condenser 34 allowed to fall back into the chamber 9. It is understood that the vapor transfer lines between the chambers would be closed by closing the valves 85, 86 and 87. 75

Another method of operation would be to close the valve 8' and open the valve 8'', thus allowing the heated oil from the heating coil to pass into the first reflux condenser 34. The lighter fractions vaporizing in the chamber 80 34 would pass through the line 42 into the condenser and the residual liquid withdrawn by opening the valves 60 and 73 to the chamber 9, where it is further heated, and the process operated as first described, returning the reflux condensate from the chambers 35, 36 and 37 to the line 64 and into line 69 by properly manipulating the valves to the preceding chambers for retreatment. 85

Another method of operation would be to close the valves 88, 89 and 90, leading to the reflux condensers and open the valves 85, 86 and 87 on the vapor transfer lines between the chambers, thus allowing all the vapors to flow into successive chambers, and out through the line 33, the valve 91 being open to the reflux condenser 37. The condensate from the reflux condenser 37 may be returned to the chamber 9 by closing the valves 65, 74 and 75, 76, 42a, 42b, 42c, and opening the valves 63, 66, 67, 68 and 73, and closing the valves 84, 60, 61, 62 and 82. By properly regulating the valves 85, 86 and 87, a differential pressure may be maintained on the oil in the chambers 10, 11 and 12. For instance, a pressure of 200 pounds may be maintained on the chamber 9, 150 pounds on the chamber 10, 100 pounds on the chamber 11 and 75 pounds on the chamber 12. This last mentioned pressure of 75 pounds may be maintained throughout the balance of the system, or a lower pressure held thereon. 110

It will be apparent to those skilled in the art that the process may be operated in many various ways by manipulating the valves shown. For instance, by regulating the valve 8', the valve 8'' being closed, a different pressure can be maintained on the heating coils than that maintained on the reaction chambers. For instance, a pressure of 400 pounds might be held on the heating coils, and the pressure reduced in the first chamber 9 to say, 200 pounds, and the process operated as above. 115 120

In addition, each reaction chamber may be heated separately by means of heating means suitably placed under them, and the fire in the furnace 19 not used. The oil could be heated in the heating coils to say, 700 degrees F., then passed to the original cham- 125 130

ber 9, which is not heated. It will be readily seen that certain of the heat units would radiate, although the reaction chambers would be preferably lagged, and that the 5 temperature would decrease in this first chamber. When the oil reaches the second chamber 10, it could be again heated by means of the individual burners explained above and further heated in the chambers 11 10 and 12 by means of individual burners.

The process and apparatus could be operated under a vacuum, by suitable vacuum pump being attached to the receiver, and the whole system regulated by the various valves 15 under this vacuum.

As an illustrative run of my process, I take a California gas oil of say, 27 degrees Baumé and heat it to a temperature of say, 400 degrees F. in the heating coil 5, and a temperature 20 of say, 750 to 850 degrees F. in the chambers 9, 10, 11 and 12, maintaining a pressure on the entire system, from heating coil to receiver, of say, 125 pounds to the square inch. By the use of this process, a 25 yield of from 70 to 80% pressure distillate, having a gravity of 48 to 50 degrees Baumé, may be obtained, which will yield 30 to 35% of commercial gasoline of a gravity of 58 to 60 degrees Baumé, when subjected to further 30 distillation, based on the original charge.

Suitable valves are interposed on the transfer line for the liquid between the various enlarged chambers, for the purpose of regulating the pressure to a nicety and to enable 35 the apparatus to be operated under differential pressures as described.

I claim as my invention:

1. In an apparatus for converting hydrocarbon oil, the combination with means for 40 initially heating the oil, means for passing the heated oil to a plurality of enlarged reaction chambers connected in series where the oil is further heated, and where vaporization takes place, means for passing the vapors released 45 in said reaction chambers to reflux condensing zones individual to each reaction chamber, means for returning the reflux condensate from each of said reflux condensing means except the first to the preceding reaction chamber for retreatment, means for 50 maintaining a vapor pressure on the entire system.

2. In an apparatus for converting hydrocarbon oil, the combination with means for 55 initially heating the oil, means for passing the heated oil to a plurality of enlarged secondary heating zones, where the oil is further heated and vaporization takes place, means for subjecting the evolved vapors from each of said 60 secondary heating zones to reflux condensation individual to each zone, means for drawing off the vapors, means for returning the reflux condensate from certain of the reflux condensing zones to the initial heating means 65 for further treatment, means for passing re-

flux condensate from the remaining reflux condensing zones to a preceding secondary heating zone and means for maintaining a pressure on the entire system.

3. A process of converting hydrocarbon oils, consisting in initially heating the oil in a coil, passing the heated oil to a plurality of enlarged secondary heating zones, connected in series, maintaining a constant level in the said secondary heating zones, heating the oil therein, to a conversion temperature, passing the vapors released from each of said secondary zones to its individual reflux condensing means, drawing off the vapors from said reflux condensing means, returning the reflux 70 condensate from certain of said reflux condensing means to one of the secondary heating zones for retreatment in returning the reflux condensate from the remaining reflux condensing means to said coil, and maintaining 75 a predetermined pressure on the system.

4. A process of converting hydrocarbon oils, consisting in initially heating the oil, passing the heated oil to a plurality of enlarged secondary heating zones connected in series, maintaining a uniform level in the said secondary heating zones, heating the oil therein to a conversion temperature, passing the vapors released from each of said secondary zones to its individual reflux condensing 80 means, drawing off the vapors from said reflux condensing means, returning the reflux condensate from all of said reflux condensing means save the first of the series to a preceding secondary heating zone for retreatment, 85 and maintaining a predetermined pressure on the system.

LEE J. GARY.
